UNITED STATES PATENT OFFICE.

WARD G. CALLENDER, OF MANSFIELD, OHIO.

SHOE-CLEANER.

1,156,751.

Specification of Letters Patent. Patented Oct. 12, 1915.

Application filed August 22, 1914. Serial No. 858,074.

To all whom it may concern:

Be it known that I, WARD G. CALLENDER, a citizen of the United States, residing at Mansfield, in the county of Richland and State of Ohio, have invented certain new and useful Improvements in Shoe-Cleaners; and I do hereby declare the following to be a full, clear, and exact description of the invention, such as will enable others skilled in the art to which it appertains to make and use the same.

This invention relates to shoe cleaners, and more particularly to a combined device for cleaning shoes which constitutes a scraper for scraping mud or the like from the surface of the soles of the shoe, and brushes positioned rearwardly of the scraper for engaging the sides of the soles and the sides of the shoe for efficiently brushing and cleaning them.

An object of this invention is the provision of a shoe cleaner as specified, which embodies a novel form of means for attaching the shoe side cleaning brushes to the supporting base upon which the scraper is formed and to provide an opening in the bottom or base of the supporting structure so as to permit the dirt cleaned from the shoe to fall therethrough.

Another object of this invention is the provision of a protective plate which is pivotally carried by the supporting structure and pivotally operable for movement over the brushes, for protecting them against freezing, rain or decomposition by atmospheric elements.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in which:

Figure 1 is a perspective view of the improved shoe cleaner showing one of the protective plates for one of the brushes positioned over the same, while the other protective plate is moved out of a protective position, Fig. 2 is a fragmentary view of one end of the improved shoe cleaner showing the same in side elevation, Fig. 3 is a

central cross sectional view through the improved shoe cleaner, Fig. 4 is a detail perspective view of a modified form of the scraping plate which is formed upon the 60 shoe cleaner, Fig. 5 is a detail fragmentary perspective view of a modified form of the improved shoe cleaner, Fig. 6 is a cross sectional view on the line 6-6 of Fig. 5, Fig. 7 is a perspective view of a link used in attaching the bristles to the supporting base of the cleaner as shown in Figs. 5 and 6 of the drawings.

Referring more particularly to the drawings, 1 designates the supporting base of the 70 shoe cleaner which is constructed of sheet metal and is cut from a single blank, having its ends 2 and 3 bent upwardly substantially at right angles to the base 1 thereof, and bent again at their terminal ends to provide 75 horizontally disposed flanges 4 and 5, to which flanges the upper edges of the brushes 6 and 7 are attached. The vertically extending ends 2 and 3 form backs or supports for the back 8 of the brushes 6 and 7, 80 and the brushes are secured to the backs in any suitable manner such as by screws or the like.

The base 1 has a scraper plate 9 formed integrally therewith, and extending along 85 one of the longitudinal edges of the base. The scraper plate 9 is bent upwardly from the base 1 and is placed slightly forwardly of the brushes 6 and 7, as is clearly shown in Fig. 1 of the drawings.

The base 1 is provided with an opening 10, which extends along the inner lower edge of the scraper plate 9, and which opening is provided to permit the dirt which is scraped from the shoe to fall downwardly through 95 the base 1 into any suitable type of receptacle or upon the ground.

The horizontally extending flanges 4 and 5 have angular plates 11 and 12 pivotally connected thereto as at 14, which angular plates are provided for pivotal movement about the point 14, for movement over the brushes 6 and 7 for covering the brushes and protecting them against atmospherical conditions, as is shown on the right-hand 100 end of Fig. 1 of the drawings. When it is desired to brush the shoe, the angled plates 11 and 12 are moved upon their pivotal points, so as to leave the brushes clean for engagement with the shoe, as is shown on 110 the right-hand end of Fig. 1 of the drawings.

In Fig. 4 of the drawings a modified form

of the scraper plate is shown, which constitutes a plate 9', formed upon the base 1'. The scraper plate 9' is bent intermediate its ends, as is clearly shown at 10', so as to more 5 efficiently fit the shape of the shoe sole and clean the dirt or mud therefrom.

In Fig. 5 of the drawings, a modified form 10 of means for attaching the brushes or brushing bristles to the supporting structure is shown. This modified form comprises a supporting base 20, which has a scraper plate 21 formed thereupon along one longitudinal marginal edge, and which has its 15 terminal ends bent upwardly forming vertical end pieces 22. The vertical end pieces 22 are bent horizontally, and curled or rolled upon themselves as is clearly shown in Fig. 6 of the drawings, forming inwardly extending flanges 23. The flanges 23 are 20 clamped downwardly and securely clamp the bristles or brushes 24 between the horizontally extending portion 25 of the end pieces 22 and the flanges 23, as is clearly shown in Fig. 6 of the drawings. The brushes 24 are 25 formed of a plurality of brushing bristles, which bristles have their terminal ends wrapped over and through links 26, which

links are inserted between the horizontal portion 25 and the flanges 23, and the flanges 23 are forced downwardly, securely binding 30 the bristles and the links 26 between the flanges 23 and the horizontal portion 25, thereby providing a novel manner of securing the brushing element to the supporting base 20 of the shoe cleaner. Angle plates 35 27 are pivotally connected as at 28 through the flanges 23, and they form protectives for the bristles or brushes 24, when the latter are not in use.

What is claimed is:

In a shoe cleaner, a supporting base formed of a single piece of sheet metal having its ends bent upwardly and horizontally to provide brush supporting elements, 40 brushes secured to said horizontally bent ends, and angled plates pivoted on a vertical axis to said horizontally bent end pieces for 45 protecting said brushes.

In testimony whereof I affix my signature in presence of two witnesses.

WARD G. CALLENDER.
